UNITED STATES PATENT OFFICE

ALEXANDER McGARY, OF NEW YORK, N. Y.

CAR ROOF CONSTRUCTION

Application filed August 18, 1927. Serial No. 213,727.

This invention relates to a novel and improved construction of freight car, and more particularly to the construction of the roof of such a car.

The invention finds particular usefulness in the roof of a car, and will be described and claimed in connection therewith, although it is to be understood that it may find use in equivalent situations.

10 In shipping certain goods, trouble has been experienced because of the fact that the goods when loaded into the car, are still warm from their manufacture, and as they cool off, sweating of the car is caused particularly on the 15 inside of the roof where the moisture collects and drips on the goods. The goods with which most difficulty has been experienced, comprise various food products such as flour, which are greatly damaged by the moisture 20 dripping thereon.

The claims against railroads caused by such damage, amount to large sums of money, and it is to avoid such damage, that I have devised the invention forming the subject matter 25 of this application.

In the accompanying drawings, in which I have shown a selected embodiment of my invention:—

Fig. 1 is a plan view of a portion of the 30 roof of a freight car;

Fig. 2 is a section on the line 2—2 of Fig. 1;

Fig. 3 is a section on the line 3—3 of Fig. 1, with the running board removed;

Fig. 4 is a section on the line 4—4 of Fig. 35 1; and

Fig. 5 is a fragmentary section of the roof showing a modified form which my invention may take.

Referring now to the drawings in detail, 40 I have shown therein a freight car roof 1, formed in a plurality of panels separated by the seam caps 2, which also act as struts to support the brackets 3 upon which are secured the running board 4 in the usual manner. The panels are usually formed of sheets of steel or other metal, the edges of the sheets being bent upwardly within the seam cap.

According to my invention, I form each 45 panel of two superposed sheets 5 and 6, these 50 sheets being formed of steel or other suit-

able metal, and disposed between these sheets I provide a heat insulating material, exemplified by a sheet 7 of paper. The sheets 5 and 6 are bent upwardly at their edges, as shown in Fig. 3, and may be riveted within the seam cap 2 in the usual manner. To insure that the paper or the like is guarded from moisture, and that the space between the sheets 5 and 6 is kept airtight, I seal the edges of the sheets as by applying thereto a suitable 60 cement 8, as indicated in Fig. 3, or by seam welding the sheets 5 and 6.

The side edges of the panels are riveted to the usual side plate angles 9, as indicated in Fig. 2, these angles being carried by the 65 standard Z bar side plate 10. The edges of the sheets are preferably bent downwardly and sealed as by seam welding, as indicated at 11, in Fig. 2.

Each end panel of the car roof is riveted 70 to the end plate angle 12, which in turn is carried by the car end 13. The sheets are bent over the angle 12, and are sealed as by seam welding at 14.

The paper which I preferably employ as 75 heat insulating material may be flat as indicated in Figs. 1 to 4 inclusive, or it may be of the corrugated type shown at 15, in Fig. 5. The corrugated form provides air spaces 80 between the metallic sheets, thus forming additional insulating means.

I have shown and described my invention as being applied to a freight car roof, because the problem which I have solved is a particularly vexatious one in connection with 85 the roof of a car. However, I do not intend to limit myself to that particular location, and I employ the term "roof" in the claims for simplicity of expression, to denote any part of a car to which my invention may be 90 found to be applicable.

I claim:—

1. A car roof panel formed of sheets of metal, one superposed on another and in close 95 proximity to each other, heat insulating material disposed between said sheets and in contact therewith, the edges of said sheets forming the edges of the panel being welded together throughout the lengths of the panel 100

edges to permanently seal the heat insulating material between said sheets.

material between said sheets.

2. A car roof formed in panels, each panel comprising sheets of metal, one superposed on another and in close proximity to each other, heat insulating material disposed between said sheets and in contact therewith, the edges of the sheets forming the edges of each panel being welded together throughout the lengths of the panel edges to permanently seal the heat insulating material of each panel between the sheets thereof, and means securing together the sealed edges of adjacent panels to form a joint.

ALEXANDER MCGARY
